UNITED STATES PATENT OFFICE.

EVERETT L. SWETT, OF GALESBURG, ILLINOIS, ASSIGNOR TO PURINGTON PAVING
BRICK COMPANY OF GALESBURG, ILLINOIS.

BRICK-FORMING DIE.

Application filed August 14, 1925. Serial No. 50,251.

This invention relates to dies for forming bricks and is more particularly adapted to a device for beveling the edges of the blocks of clay after the same leave the brick making machine.

The purpose of beveling the edges of a brick is to enable such bricks to be used as paving blocks and more particularly those which are to be placed in the streets or highways of a hill so as to increase the traction 10 of vehicles and animals passing over the blocks.

Another important object of the invention is to provide a brick forming die of the 15 above mentioned character wherein means is provided for cutting the clay material into several bricks after the edges thereof have been bevelled.

A still further object is to provide a brick 20 forming die of the above mentioned character which is of such construction as to permit the same to be readily and easily installed on the front of any well-known type of brick making machine, the same being 25 simple in construction, inexpensive, and furthermore adapted to the purposes for which the same is designed.

Other objects and advantages of this 30 invention will become apparent during the course of the following description.

In the accompanying drawings forming part of this specification and in which like numerals are employed to designate like parts throughout the same:

Figure 1 is a front elevation of the brick forming die embodying my invention;

Figure 2 is a rear elevation;

Figure 3 is a top plan view;

Figure 4 is a transverse section taken approximately on line 4—4 of Figure 3;

Figure 5 is a detail perspective view of the clamping means associated with the cutting wire; and

Figure 6 is a detailed perspective view of 45 a paving block wherein the edges thereof are bevelled after the same have been passed through my die.

In the drawings, wherein for the purpose 50 of illustration is shown a preferred embodiment of my invention, the numeral 1 designates generally the member comprising my brick forming die, the same being preferably a substantially rectangular shaped frame of a suitable width, the front and rear ends of which are open.

The inner walls of the substantially rectangular shaped frame 1 gradually converge from the rear to the front of the frame and as is clearly illustrated in Figures 3 and 4 of the drawings, the inner walls are slightly 60 rounded. In this manner the opening of the frame gradually decreases in size from the rear to the front of the frame.

The corners of the frame are bevelled as indicated at 2 to provide several forming 65 faces the purpose of which will be herein-after more fully described and is shown more clearly in Figures 1, 2 and 4 of the drawings, these faces gradually increase in width from the rear to the front of the 70 frame.

Formed on the inner wall of the top of the frame at the intermediate portion thereof and extending from the rear to the front of the frame is the triangular shaped rib 3, 75 a similar rib 4 is formed on the inner wall of the intermediate portion of the bottom of the frame and also extends from the rear to the front of the frame. These ribs are disposed in vertical alignment and also 80 gradually increase in size from the rear to the front of the frame. The ribs cooperate with the adjacent bevelled forming faces 2, it being understood, of course, that the ribs also form bevel forming faces. 85

A transversely extending cutting wire 5 is disposed across the front face of the die and the respective ends of the wire are received in suitable grooves provided therefor in the inner rear faces of the clamping 90 members 6. The groove formed in the rear face of each of the clamping members is indicated at 7. Each of the clamping members is provided with the openings 8 through which extend the stud bolts 9, the threaded 95 ends of which are threaded into suitable threaded openings provided therefor in the front face of the top and bottom walls of the frame so that the cutting wire will be secured in a taut position across the front 100 of the die. The purpose of the wire frame is to provide a means whereby the slab of clay which is forced through the die will be cut into two bricks. It is, of course, understood that I do not wish to limit myself to 105 the provision of a single wire or one pair of ribs and any number of ribs or wires may be provided as is desired for forming any number of bricks that may be desired.

Dies adapted to be advanced on the front 110

of any well known type of brick making machine so that the bricks or the slabs of clay which are discharged from the machine in the form of blocks will be forced into the rear of the frame 1, and as the clay material passes through the frame in the direction of the arrows, the faces 2 and the ribs 3 and 4 will cooperate to form a bevel on the outer edges of the slab of clay as well as 10 opposed bevels on the top and bottom of the intermediate portion of the blocks and a cutting wire to pass through the bevelled portion of the slab and cut between the opposed bevels formed in the intermediate portions at the top and bottom of the clay material. In this manner, a pair of blocks will be formed, the edges of each block being bevelled and such a block is illustrated at A in Figure 6 of the drawings.

20 Ordinarily, the clay material which passes through the brick making machine is cut from the side leaving the length of the bricks the full width of the slab. With the present attachment, the bricks will be cut 25 the same way but further apart so that when the clay material passes through my improved die, the pair of bricks which are discharged from the die will each be of the same size as the ordinary bricks manufactured by any well known type of brick making machine.

By beveling the edges of the brick in the manner as above described, a brick will be provided for use as a paving block in streets 35 or highways which form a hill, and the bevelled edges and the adjacent paving blocks or bricks will cooperate to increase the traction of vehicles and of animals travelling over the surface.

40 The simplicity in which my improved die is constructed enables the same to be manufactured at a very low cost and may furthermore be easily and readily attached on a brick making machine of any conventional 45 construction without necessitating any material alterations of the latter. Furthermore, a device of the above character will at all times be positive and efficient in carrying out the purposes for which it is designed.

50 While I have shown the preferred embodiment of the invention, it is to be understood that minor changes coming within the field of invention claimed, may be resorted to if desired.

What is claimed is:—

1. A brick forming die of the class described, comprising a substantially rectan-

gular frame open at its front and rear, the inner walls of the frame converging gradually toward the front, bevel forming faces arranged in the corners of the inner walls of the frame, substantially triangular shaped ribs formed on the inner walls on the top and bottom respectively in the intermediate portions thereof, said bevel forming faces and the aforementioned ribs gradually increasing in width from the rear of the frame to the open front thereof, the bevel forming faces and the ribs cooperating to bevel the edges of the brick material which is forced through the frame from the rear to the front thereof, said ribs forming a pair of opposed bevels at the intermediate portion in the top and bottom faces thereof, and a cutting wire extending transversely across the front face of the frame adjacent said ribs for cutting between the opposed bevelled edges formed by the ribs whereby a pair of blocks is formed, the edges of which are bevelled.

2. A brick forming die of the class described, comprising a substantially rectangular frame open at its front and rear, the inner walls of the frame converging gradually toward the front, bevel forming faces arranged in the corners of the inner walls of the frame, substantially triangular shaped ribs formed on the inner walls of the top and bottom respectively in the intermediate portions thereof, said bevel forming faces and the aforementioned ribs gradually increasing in width from the rear of the frame to the open front thereof, the bevel forming faces and the ribs cooperating to bevel the edges of the brick material which is forced through the frame from the rear to the front thereof, said ribs forming a pair of opposed bevels at the intermediate portion in the top and bottom faces thereof, a cutting wire extending transversely across the front face of the frame adjacent said ribs for cutting between the opposed bevelled edges formed by the ribs whereby a pair of blocks is formed, the edges of which are bevelled, and clamping members for securing the cutting wire in a taut position, the same comprising a pair of plates secured to the front face of the frame at the top and bottom thereof respectively, the inner face of each plate being provided with a transversely extending groove for receiving the respective end of the cutting wire.

In testimony whereof I affix my signature.

EVERETT L. SWETT.
